PETER M. SHERWOOD, OF NEW YORK, N. Y.

Letters Patent No. 84,384, dated November 24, 1868.

IMPROVEMENT IN BOTTLE-FILLING APPARATUS.

The Schedule referred to in these Letters Patent and making part of the same.

To all whom it may concern:

Be it known that I, PETER M. SHERWOOD, of the city, county, and State of New York, have invented a new and useful Improvement in Bottle-Filling Machine; and I do hereby declare that the following is a full, clear, and exact description thereof, which will enable those skilled in the art to make and use the same, reference being had to the accompanying drawings, forming part of this specification.

This invention relates to improvements made in a bottle-filler, for which Letters Patent were issued to Theodore Cochen, dated the 5th day of June, 1866, the entire interest in which patent has been duly assigned to me; and the invention consists in the arrangement and construction of other siphon-valves, in combination with the reservoir described in said patent, and which are shown in the present application, and in the construction of the valve-movements of the siphons, and in the application of other appendages to the reservoir, and in combination therewith, as will be hereinafter more fully described.

Figure 1 is a sectional elevation of the reservoir, showing the parts which embrace my improvements, with some of the improvements themselves.

Figure 2 represents a siphon, with a valve at its receiving-end, and attached to the inner side of the reservoir.

Figure 3 shows a siphon arranged to admit discharge-tubes or nozzles of different sizes.

Figure 4 represents a top view of the device for holding bottles by the neck, and keeping them in place while being filled, the position of which is seen in fig. 1, as attached to the reservoir by slotted arms.

Similar letters of reference indicate corresponding parts.

A is the reservoir, which is a water-tight vessel, as described in the patent before alluded to, and is provided with a feed-pipe and valve, which valve is governed by a float in its opening and closing, so that the liquid is allowed to enter the reservoir only as it is required for filling the bottles.

The particular purpose for which this apparatus is intended is filling bottles, jugs, kegs, or cans, and other vessels with any kind of liquid; and the float in the reservoir is so adjusted that the liquid is kept at a uniform height in the reservoir.

B is an adjustable shelf, attached to the outside of the reservoir by the slotted arms C, and held in place by bolts on each side, as seen at d.

The bottle on the shelf (seen in red) is placed as being filled by the siphon, marked E.

The delivery-end of this siphon, E, is provided with a valve, with an extension-stem, e, the valve being opened when the stem strikes the bottom of the bottle or vessel.

The length of the stem can be adjusted to suit the vessel by screwing or unscrewing the stem.

The other (or receiving) end of this siphon is also provided with a valve, which is opened and closed by the slotted arm f, which is attached to the inner side of the reservoir.

The valve g is attached to the flanged sleeve h.

The flange or collar i has a pin, j, which slides in the slot of f.

The siphon is hinged to the top of the reservoir at q, so that when the delivery-end is drawn from the reservoir, the valve is closed, and when it is pushed towards the reservoir, it is opened.

The siphon H is open at its receiving-end, but its delivery-end is provided with a valve which acts automatically.

l is the valve, whose stem is attached to a collar, m, by the wires n.

o is a collar on the siphon.

p is a spiral spring, between the two collars.

In filling, the nozzle of the bottle is pushed against the collar m, which lifts the valve, and the liquid flows in.

When the bottle is removed, the spring closes the valve.

This siphon (as well as all the others) is hinged to the top of the reservoir, as seen at q.

J, fig. 2, represents a siphon attached to the inner front side of the reservoir, and provided with a valve, which is actuated by working the siphon back and forth on its pivot-hinge q.

The end of the siphon is provided with packing, and packing is also attached to the reservoir.

The packing of each is seen in red at r.

The extent of the movement is governed by a slotted plate and pin, seen at S, and the valve is closed by the reaction of the spring t, which draws the two packing-plates (or valve and seat) together, making a tight joint.

K, fig. 3, represents a siphon with its end arranged to attach delivery-tubes of different sizes.

For this purpose I attach a collar, u, to the siphon, and cut a screw-thread therein, so that any delivery-tube, provided with a corresponding screw, can be attached, as seen in the drawing.

For measuring out definite and fractional quantities of liquid from the reservoir, I provide a separate vessel, L, with a glass or transparent portion marked off or graduated, so as to indicate certain quantities.

This vessel I attach by a set-screw to the cock v in the reservoir.

The delivery-tube to this measuring-vessel is similar in its construction to what is described in the patent, but the valve v' is made tapering, and the sliding sheath or sleeve w is made to fit.

The liquid enters the tube laterally from the reservoir through suitable orifices, and is discharged through the lateral orifices i. The sleeve w has a flange, x, against which the bottle is pressed in filling.

The collar is attached to an enlarged portion, y, of the sleeve, which enlarged portion encloses a spiral

2

spring, and is provided with a bayonet-fastening device, as seen at *z*, so that the valve can be left open as long as may be desired.

When the sleeve is released from the fastening-pin, the vessel is closed by the recoil of the spring.

This bayonet-fastening is applied to the delivery-tube of the measuring-vessel *L*, the fastening-pin being seen at *2*.

For holding the bottles by the neck, or keeping them in place when being filled, I attach the bar *a* to the reservoir, and make it adjustable thereon by two slotted arms, *b*, (one on each side,) as in the case of the shelf *B*.

By the slotted arms, the bar *a*, as well as the shelf *B*, is fastened out or in, so as to accommodate the bottles or vessels, and they are both made otherwise adjustable by the thumb-screws *d* at their ends, as seen in the drawing.

The tapering ground valve *v'*, and sleeve *w*, and also the bayonet-fastening, are applied to the filling-faucet, seen at *y'*, fig. 1.

This faucet screws into the reservoir, and is designed for filling bottles independently of the other apparatus.

I claim as new, and desire to secure by Letters Patent—

1. The valves, as arranged on the interior and exterior ends of the siphon *E*, said siphon being combined with a reservoir, substantially as described.

2. The valve *l*, arranged as described, on the delivery-end of the siphon *H*, with the collars *m o*, spring *p*, and yoke *n*, substantially as and for the purpose specified.

3. The bayonet-fastening *z*, in combination and arranged with the tapering valve *v'*, the spiral spring, and the sleeve *w*, having the enlarged portion *y*, and the flange *x* adapted to fit upon the mouth of the bottle, all operating as described, whereby, as the bayonet-catch is released, the sleeve *w* is thrown outward, to close the orifice *i* in the valve *v'*, as and for the purpose specified.

4. The C-shaped siphon *J*, hinged to the top of the reservoir at *g*, and provided at its interior end with a packing, *r*, adapted to work against a packing affixed to the reservoir *A*, the whole constructed and operating in the manner and for the purpose specified.

5. The adjustable bar *a* and shelf *B*, constructed and arranged substantially as shown and described, in combination with the reservoir *A*, for the purposes specified.

6. The faucet *y'*, embracing the tapering valve *v'*, sleeve *w*, and the bayonet-fastening *z*, substantially as described, and for the purposes set forth.

The above specification of my invention signed by me, this 17th day of June, 1868.

PETER M. SHERWOOD.
